UNITED STATES PATENT OFFICE.

MICHAEL STAUNER, OF WALKER, MINNESOTA.

STUMP-PULLER.

1,177,454.

Specification of Letters Patent. Patented Mar. 28, 1916.

Application filed May 13, 1913. Serial No. 767,383.

To all whom it may concern:

Be it known that I, MICHAEL STAUNER, citizen of the United States, residing at Walker, in the county of Cass and State of Minnesota, have invented certain new and useful Improvements in Stump-Pullers, of which the following is a specification.

This invention relates to stump pullers or extractors and more particularly to that type wherein a weight is adjustably mounted upon a pivotally supported beam for generating the lifting or pulling power required in extracting or removing stumps from the soil.

15 The primary object of the invention contemplates the provision of an adjustable carrier adapted to be slid throughout the length of the pivoted beam for elevating and adjusting the weight member carried thereby, this arrangement permitting stumps of various size to be extracted or removed without altering or affecting the construction of the device other than adjusting the said carrier.

25 A further object of the invention resides in the provision of means whereby the said pivoted beam may be broken centrally so as to permit that portion upon which the carrier is adjustably mounted, to be swung 30 or dropped into engagement with the ground, in which position the entire device is in condition to be transported or conveyed by any suitable motive power from place to place.

35 The invention still further resides in the provision of a specially devised carrier upon which is arranged a suitable pawl adapted to engage the teeth of a rack bar carried by the beam for locking the said 40 carrier against movement when proper adjustment thereof is accomplished.

The above and additional objects are accomplished by such means as are illustrated in their preferred embodiment in the accompanying drawings, described in the following specification and then more particularly pointed out in the claims which are appended hereto and form a part of this application.

50 In describing my invention in detail reference will be had to the accompanying drawings wherein like characters denote like or corresponding parts throughout the several views and in which:—

55 Figure 1 is a side elevation of a device

or machine constructed in accordance with my invention; Fig. 2 is a similar view, the beam being swung into an inoperative position, the dotted lines illustrating the position of the beam during conveyance; Fig. 3 60 is a top plan view of the device; Fig. 4 is a longitudinal sectional view; Fig. 5 is an enlarged detail perspective view of the carrier; and Fig. 6 is a fragmentary view illustrating the manner in which the rack bar is 65 adjustably supported.

Referring now to the drawings wherein is illustrated the preferred form of my invention the numeral 1 designates the main frame of the machine, the said frame being 70 supported through the medium of wheels 2 arranged upon the main axle 3 of the machine. The axle 3 is preferably rectangular in cross section and has bolted thereto as at 4 a suitable bracket 5, the latter having pivotally arranged thereupon the main beam 6 of the device, the pin 7 upon which the said beam is supported being removably inserted in an opening provided therefor within the said beam 6, this construction permitting the beam to be removed from the said axle should occasion demand. The rear end of the main beam 6 is provided with a central projection 8, the said projection adapted to fit between the portions 9 of the bifurcated end of the extended portion of the said beam 10. A pin 11 carried by the beam 6 by means of a chain 12 is adapted to pass through alined openings 13 of the said projection 8 and portions 9 for supporting the 80 said extended portion 10 of the beam parallel with the main portion 6, as the said extension 10 is pivoted as at 14 to the extremity of the said beam 6, this construction permitting the extended portion 10 to break or 85 drop into engagement with the ground when the pin 11 is withdrawn or removed from the openings 13 provided therefor.

An elongated opening or cut out portion 15 is formed in the extended portion 10 of the beam 6 the said opening extending throughout the major portion of the length thereof and having a sprocket chain 16 arranged therein over sprocket wheels 17 and 18 respectively mounted at the forward and rear ends of the said opening. A gear wheel 19 is keyed or otherwise secured or mounted upon the same shaft as the sprocket wheel 17, the said gear wheel being disposed upon the exterior of the beam and adapted to 100 105 110

mesh into a large gear 20 likewise arranged upon the exterior of the beam adjacent the pivot point 14. The said gear 20 is provided with a crank handle 21 by means of which motion is imparted thereto where it is transmitted to the sprocket chain 16 through the medium of a small gear wheel 19 and the wheels 17 and 18 upon which the sprocket chain is arranged.

10 A carrier, designated in its entirety by the numeral 22 is slidably mounted upon the extended portion 10 of the beam, the said carrier having a wheel 23 rigidly mounted thereupon and provided with teeth 24 against which the links of the chain 16 abut, this construction imparting movement to the carrier according to the movement of the chain, as the said wheel 23 being stationary, and the teeth thereof engaged by the sprocket chain sliding movement is imparted thereto. The body portion 25 of the carrier is preferably semicircular in form and is arranged over the extended portion 10 of the beam as is clearly shown in Fig. 4 of the drawings, 20 the said body portion having an extension or depending portion 26 securely fastened thereto for the purpose of supporting a weight member 27.

Adjustably mounted upon the exterior of 30 the beam 10 upon each side thereof I provide a rack bar 28 one end of which is inclosed within a suitable housing 29 and attached thereto by means of an expansion spring 30 arranged within the said housing. Ratchet teeth 31 are formed upon the forward end of the rack bar 28 the said teeth meshing into a segmental rack 32 carried by the beam 10, and movement being imparted to the said rack by means of a hand 35 lever 33 secured to and depending therefrom. By operating or actuating the hand lever 33 it will be seen that movement is imparted to the rack bar 28 this slight movement permitting minute adjustment of the 40 carrier retaining mechanism to be herein-after fully described.

A lever 34 is pivotally supported as at 35 over the carrier body portion 25, the said lever having a hook member 36 secured to one end thereof adapted to engage a staple 37 of the carrier, the provision of which will prevent movement of the said lever when so desired. The opposite end of the lever 34 is connected to a bail 38, the said bail adapted 50 to straddle the body portion 25 of the carrier and have secured at each end a vertically slidable pawl 39, the latter being supported or retained in proper place by means of slide-ways 40 fastened to the depending portion 55 26 of the carrier. The pawls 39 being arranged directly over the rack bars 38 of the beam, it will be seen that minute adjustment of the carrier is permitted and that the same is locked in adjusted position upon the beam 60 by reason of the engagement between the

said pawls 39 and the teeth of the rack bars 28, the latter extending upon each side of the beam throughout the length of the sprocket chain 16 arranged upon the interior of the opening 15 formed within the said beam. Guide-ways 41 are also secured to the depending portion 26 of the carrier, the said guide-ways being disposed at right angles to the guide-ways 40 and adapted to form a support or rest for the rack bars 28 which extend therethrough thereby at all times supporting the said rack bars in direct alinement with the pawls 39 above mentioned.

Having described the manner in which 80 the carrier is adjusted upon the beam portion 10 it now remains to describe the manner in which the said beam portion is elevated or swung upon its pivot point created by the main axle 3 of the machine. A hook shaped member 42 is formed integrally with and upon the rear extremity of the extended portion 10 of the beam, the said member being connected to a drum 43, revolvably mounted upon the main frame 1, by means of a 85 rope 44 adapted to pass over a roller 45 arranged between brackets 46 carried by the said main frame. A ratchet wheel 47 is secured upon the extremity of the drum shaft or drum 43, the said ratchet having a handle 48 provided therefor by means of which rotation is imparted to the drum 43, thus permitting the rope 44 to be wound thereupon for elevating the extended portion 10 of the beam. To prevent unwinding of the ratchet 47 a pawl 49 is pivoted as at 50 upon the frame side 1 of the machine.

A supporting bracket 51 is secured to the under face of the main beam 6 and is adapted to partially surround the main shaft or 105 axle 3 of the device, this construction permitting the beam to be freely swung with the axle 3 at its pivot point.

The forward extremity of the main beam 6 has formed integrally therewith a pair of spaced apart hook shaped members 52, the said members adapted to be forced beneath the stump to be extracted in a manner to be hereinafter fully described.

Pawls 53 are pivoted as at 54 to the rear end of the main frame 1, the said pawls adapted to engage the ground or soil to prevent backward movement of the device during extraction or stump pulling operation, hooks 55 being provided for supporting the said pawls out of engagement with the ground during transportation or conveyance of the machine.

A bracket 56 is secured to the rear end of the beam portion 10 and is yieldably supported by means of a spring 57 arranged beneath the hook shaped member 42 of the beam, this arrangement allowing the said beams to be broken centrally or swung upon its pivot 14 without engaging or contacting

the ground as the said bracket 56 will yieldably support the said beam portion and provide a cushion therefor.

Having described in detail the construction of the device or machine, the operation of the same will now be set forth.

The machine is first wheeled adjacent the stump to be extracted and the hook shaped member 52 of the main beam 6 forced beneath or into the said stump and the pawls 53 dropped into engagement with the ground. The extended portion 10 of the beam is then raised into a position parallel with the main portion 6 by the manipulation 15 of the handle 48, the said handle adapted to operate the drum 43 and the rope 44 which in turn elevates the hook shaped member 42 of the extended portion 10 of the beam. After swinging the said ex-

20 tended portion into alignment with the main portion 6, the pin 11 is inserted through the openings 13 provided therefor thereby effecting a support for the said extended portion and supporting the said portion in

25 proper operative position. The carrier 22 is then adjusted by means of the crank handle 21 the said handle controlling the movement of the sprocket chain 16 which engages the stationary toothed wheel 23 of the

30 carrier for adjusting the latter throughout the length of the said sprocket chain upon the extended portion 10 of the beam. After properly adjusting the carrier as above set forth the hook 36 is released from the sta-

35 ple 37 and the pawls 39 are free to engage the teeth of the rack bars 28 which engagement will support the said carrier in the desired adjusted position. Should a minute adjustment be required, operation of the 40 handle 33 will allow the said rack bars to slightly move by reason of the spring supports inclosed within the casing 29 of the said rack bars.

By adjusting the carrier as above described stumps of various size may be extracted as the movement of the said carrier toward the rear end of the beam portion 10 will cause the said beam to swing upon its pivotal support and thereby raise the hook shaped member 52 and the stump beneath which it is arranged.

It will be seen from the above, taken in connection with the accompanying drawings that the beam may be divided or broken centrally and the extended portion 10 dragged over the ground during conveyance of the machine, the bracket 56 forming a cushion therefor; that the said beam may be swung into alignment with the main portion 6 thereof by the manipulation or operation of the drum 43; and that the construction of the carrier 22 is such as to permit adjustment thereof throughout the entire length of the sprocket chain 16 to which it is at-

tached through the medium of the teeth 24 of the stationary wheel 23.

In reduction to practice, I have found that the form of my invention, illustrated in the drawings and referred to in the above description, as the preferred embodiment 70 is the most efficient and practical; yet realizing that the conditions concurrent with the adoption of my device will necessarily vary, I desire to emphasize the fact that various minor changes in the details of construction, proportion and arrangement of parts may be resorted to, when required, without sacrificing any of the advantages of my invention, as defined in the appended claims. 75

Having thus fully described my invention, what I claim as new and desire to secure by Letters Patent, is:—

1. A stump puller, including a frame, a beam pivotally supported upon the frame, a carrier slidably mounted upon the beam, a rack positioned upon the beam and adapted to hold the carrier in adjusted position, a sprocket wheel arranged upon the beam for the purpose of adjusting the carrier on the 90 rack throughout the entire length of the beam, and means including a plurality of gears carried by said beam for operating the sprocket.

2. A stump puller including a frame, a beam pivotally supported upon the frame, said beam having an elongated opening formed therein, a sprocket chain arranged within the said opening and extending throughout the length thereof, a carrier 100 slidably mounted upon the said beam, the said carrier adapted to engage the said sprocket chain for adjusting the former throughout the length of the said beam, gear mechanism carried by the said beam 105 for operating the said sprocket and means carried by the main frame of the machine for swinging the said beam, as and for the purpose set forth.

3. A stump puller including a frame, a beam pivotally supported upon the frame, the said beam having an elongated opening formed therein, a sprocket chain arranged within the said opening, the said chain adapted to extend throughout the greater 115 portion of the said beam, a carrier slidably mounted upon the said beam, a fixed wheel arranged upon the said carrier, the said wheel adapted to engage the said sprocket chain for sliding the said carrier according 120 to the movement of the said chain, and a weight member depending from the said carrier adapted to swing the said main beam about its pivot point for extracting the stump engaged thereby. 125

4. A stump puller including a frame, a beam pivotally supported upon the frame, the said beam having an elongated opening

formed therein, a sprocket chain arranged within the said opening, the said chain adapted to extend throughout the greater portion of the said beam portion, a carrier 5 slidably mounted upon the said beam, a fixed wheel arranged upon the said carrier, the said wheel adapted to engage the said sprocket chain for sliding the said carrier according to the movement of the 10 said chain, gear mechanism carried by the said beam for operating the said sprocket chain and means arranged upon the said carrier for supporting the same in adjusted position upon the said beam, as and for the 15 purpose set forth.

5. A stump puller including a frame, a beam pivotally supported upon the frame, the said beam having an elongated opening formed therein, a sprocket chain arranged 20 within the said opening, the said chain adapted to extend throughout the greater portion of the said beam portion, a carrier slidably mounted upon the said beam, a fixed wheel arranged upon the said carrier, the said wheel adapted to engage the 25 said sprocket chain for sliding the said carrier according to the movement of the said chain, gear mechanism arranged upon the exterior of the beam for operating the 30 said sprocket chain, a rack bar carried by the said beam, and means including pawls arranged upon the said carrier adapted to engage the said rack bar for supporting the said carrier in adjusted position upon 35 the said beam.

6. A stump puller including a frame, a beam pivotally supported upon the frame, the said beam having an elongated opening formed therein, a sprocket chain arranged 40 within the said opening, the said chain adapted to extend throughout the greater portion of the said beam, a carrier slidably mounted upon the said beam, a fixed wheel arranged upon the said carrier, the said 45 wheel adapted to engage the said sprocket chain for sliding the said carrier according to the movement of the said chain, a weight member depending from the said carrier, rack bars arranged upon the said beam, the 50 said bars adapted to extend throughout the length of the said opening, a lever pivotally supported by the said carrier and pawls operated by the said lever adapted to engage the teeth of the said rack bar for supporting the carrier in adjusted position upon the said extended portion of the beam.

7. A stump puller including a frame, a beam pivotally supported upon the frame, the said beam having an elongated opening formed therein, a sprocket chain arranged 55 within the said opening, the said chain adapted to extend throughout the greater portion of the said beam portion, a carrier slidably mounted upon the said

beam, a fixed wheel arranged upon the said 65 carrier, the said wheel adapted to engage the said sprocket chain for sliding the said carrier according to the movement of the said chain, a weight member depending from the said carrier, rack bars adjustably 70 arranged upon the said extended portion of the beam, means including a segmental rack adapted to engage teeth formed upon the said rack bar for adjusting the latter, a lever pivotally supported upon the said carrier, vertically slidable pawls adapted to engage the teeth of the said rack bar for supporting the said carrier in adjusted position upon the said extended portion of 75 the beam.

8. In a stump puller, a wheeled frame, a beam pivotally supported upon the said frame, a weighted carrier slidably mounted upon the beam, a toothed wheel rigidly mounted upon the said carrier, means operated within the said beam adapted to engage the said tooth wheel for sliding the said carrier, throughout the length of the said extended portion of the beam, and means including vertically slidable pawls arranged 80 upon the said carrier, rack bars adjustably mounted upon the said beam for supporting the said carrier in adjusted position, as and for the purpose set forth.

9. In a stump extractor, a fulcrumed beam, flexible means for elevating one end of said beam, the opposite end of the beam being disposed for engagement with the stump acted upon, and a weighted carrier adjustable throughout the length of said beam section adapted to rock the beam during a stump extracting operation.

10. In a stump extractor, a main beam fulcrumed intermediate its ends, means engaging the said beam for elevating one end 105 of the beam, the opposite end of the said beam being disposed for engagement with the stump acted upon, and means including a carrier adjustable throughout the length of the said beam to rock the said beam during a stump extracting operation, as and for the purpose set forth.

11. In a stump extractor, a fulcrumed beam, means for elevating one end of the said beam, the opposite end of the said beam 115 being disposed for engagement with the stump acted upon, a beam section pivoted to the said beam, adapted to be normally maintained in alinement with said beam, a weighted carrier adjustable throughout the greater portion of the length of the said beam section, and means for supporting said carrier in the desired adjusted position, as and for the purpose set forth.

12. In a stump extractor, a fulcrumed beam, one end of the said beam being disposed for engagement with the stump acted upon, a carrier adjustable upon said beam,

- endless means for effecting such adjustment, and means for locking the carrier in the desired adjusted position, as and for the purpose set forth. 50
- 5 13. In a stump extractor, a fulcrumed beam, one end of the said beam being disposed for engagement with the stump acted upon, a carrier slideable upon the said beam, a weight member movable with said carrier, 10 endless means for imparting movement to said carrier independent of the beam, and means for locking the said carrier in the desired adjusted position, as and for the purpose set forth. 15 14. In a stump extractor, a fulcrumed beam, a carrier movable upon said beam, automatic means including an endless chain disposed for engagement with the said carrier to provide for the adjustment thereof, 20 means for locking the said carrier in the desired adjusted position, the movement of the said carrier in one direction upon the said beam adapted to rock the same, as and for the purpose set forth. 25 15. In a stump extractor, a fulcrumed beam, one end of the beam being disposed for engagement with the stump acted upon, a carrier movable upon the said beam, a rack bar supported by said beam, and automatic means carried by the said carrier adapted for engagement with the said rack bar to maintain the said carrier in the desired adjusted position, as and for the purpose set forth. 30 35 16. In a stump extractor, a fulcrumed beam, one end of the said beam being disposed for engagement with the stump acted upon, a weight member movable throughout the length of an opening formed within the said beam, an endless chain operable within the said opening, means for operating the said chain and means supporting the said weight member and engaging the said chain to provide for the adjustment of the former, 40 as and for the purpose set forth. 45 17. In a stump extractor, a fulcrumed beam, a movable carrier, a rack bar, means carried by the said carrier adapted for en- 55 gagement with the said rack bar to maintain the said carrier in the desired adjusted position, and means for adjusting the said rack bar to provide for the minute adjustment of the carrier, as and for the purpose set forth. 60 18. In a stump extractor, a fulcrumed beam, an adjustable carrier, a rack bar, means carried by the said carrier and adapted for engagement with the said rack bar to maintain the carrier in the desired adjusted position, and means including a seg- 65 mental rack adapted for engagement with the teeth of the said rack bar to shift the same and provide for minute adjustment of the carrier, as and for the purpose set forth. 70 19. In a stump puller, a fulcrumed beam, a beam section pivoted thereto, means for supporting the said beam section in alignment with the said beam, and means for raising and lowering the said beam section independent of the said beam, as and for the purpose set forth. 75 20. In a stump extractor, a wheeled frame, a fulcrumed beam supported thereby, means for rocking the said beam during a stump extracting operation, and means for supporting the said frame against movement in any direction during a rocking of the said beam. 80 21. In a stump extractor, a fulcrumed beam, a carrier adjustable thereupon, means supported by the beam for adjusting the carrier, an adjustable rack bar, a pawl movable upon the said carrier and adapted for engagement with the said rack bar to maintain the said carrier in the desired adjusted position, a fulcrumed lever to which the said pawl is secured, and means for locking the said lever inoperative, as and for the purpose set forth. 85 In testimony whereof I affix my signature 90 in presence of two witnesses.

MICHAEL STAUNER.
